Application December 13, 1947, Serial No. 143,118

Term of patent 14 years

(Cl. D80—5)

To all whom it may concern:

Be it known that I, Samuel Oliver Levy, a citizen of the United States, and a resident of the city of New York, in the county and State of New York, have invented a new, original, and ornamental Design for a Display Stand or the like, of which the following is a specification, reference being had to the accompanying drawing constituting a part thereof in which:

Fig. 1 is a front elevational view of a display stand, showing my new design.

Fig. 2 is a rear elevational view thereof, and

Fig. 3 is a top plan view thereof partially in section.

I claim:

The ornamental design for a display stand or the like, substantially as shown.

SAMUEL OLIVER LEVY.
